UNITED STATES PATENT OFFICE

GEORG GRUSCHKE, OF BERLIN-WILMERSDORF, GERMANY, ASSIGNOR TO SIEMENS & HALSKE, AKTIENGESELLSCHAFT, OF SIEMENSSTADT, NEAR BERLIN, GERMANY, A CORPORATION OF GERMANY

LOUD SPEAKER WITH ACTUATING SYSTEMS OF DIFFERENT TYPES

Application filed September 4, 1929, Serial No. 390,239, and in Germany September 7, 1928.

The invention concerns loudspeakers which are to reproduce, as true to nature as possible, a wide frequency range without favoring individual frequency groups. The 5 oscillations of the sound must be reproduced without distortion with respect to their absolute size as well as corresponding to the proportion of the sound intensity of the individual frequency bands.

10 The loudspeakers known in the prior art with a single actuating system emphasize especially certain frequency groups in the reproduction. The electromagnetic actuating systems, for instance, are very well adapted 15 for the middle range frequencies, the electrostatic for the high frequencies and the electrodynamic for the low frequencies. These characteristic differentiating qualities have already been used to insure a natural pure reproduction of musical offerings in the manner that the talking currents were conveyed simultaneously to three loudspeakers separated from one another and operating according to different principles, and disposed close 20 together, for instance in a common housing.

According to the invention several different actuating systems are combined in the manner that they influence a membrane which is common to all. By this means the 30 loudspeaker may be kept down to a small size and to lighter weight. Disturbing interferences and surges are avoided for the reason that the sound waves are radiated from a common membrane in contrast to the arrangements known in the prior art.

The figures show an embodiment of the idea of the invention by way of example. The talking currents coming from the amplifier or from an electric sound box are conveyed to the telescopic coil 1 of an actuating system 2 operating according to the electrodynamic principle. The conical membrane 4 is connected with the coil 1 by means of a small pin 3 and is covered by a metallically 40 conducting coating or is made of metal entirely. To the membrane 4 is applied, with the insertion of a flexible dielectric 5 a second metallic layer 6. Both metallic coatings form, with the intermediate layer, a condenser whose one plate is movable and is,

with the variation of the electric field, more or less strongly attracted to the fixed plate. Both plates are connected, if necessary, with the insertion of amplifiers or transformers, with the same current source which also supplies the telescoping coil of the electrodynamic system. The membrane 6 follows the oscillations of the membrane 4 immediately since it operates practically inertialess. Over the forced oscillations, produced by 55 membrane 4 which is excited by the electrodynamic system, are superimposed the oscillations which have been impressed by the talking currents upon the electrostatic system and whose middle and lower frequencies are quite strongly damped by the elastic dielectric, while the high frequencies with their smaller amplitude may oscillate freely. These high frequencies are lacking in the 60 electrodynamic system since the latter, due to its relatively large inertia, cannot, without retardation, follow the oscillations following 65 one another in rapid succession. By means of the cooperation of the two systems there is created a loudspeaker which reproduces with 70 uniform good quality the entire frequency range.

In similar manner the electromagnetic system may be combined with the electrostatic or electrodynamic systems.

In the reproduction of many musical offerings it is suitable to have the talking currents act upon one system only. The lead-in conductors are, therefore, supplied with switches which interrupt the circuit of the talking 80 current.

I claim:

1. An acoustic device comprising a vibratile member having a conducting surface, means including a winding adapted to be 90 traversed by a modulated electric current for vibrating said member, and a second conducting surface electrostatically cooperating with the first mentioned conducting surface for causing additional vibration of said member.

2. An acoustic device comprising a vibratile member consisting of a pair of conducting surfaces and an insulating medium therebetween, said conducting surfaces being adapted for movement relative to each other, 100

and means for vibrating said vibratile member.

3. An acoustic device comprising a pair of conducting surfaces insulated from each other and adapted to vibrate relative to each other, and means for vibrating said surfaces as a whole, said means including a winding adapted to be traversed by acoustically modulated electrical currents.

10 In testimony whereof I affix my signature.

GEORG GRUSCHKE.
